UNITED STATES PATENT OFFICE.

WILLIAM R. McKEEN, JR., OF OMAHA, NEBRASKA, ASSIGNEE TO McKEEN MOTOR CAR COMPANY, OF OMAHA, NEBRASKA, A CORPORATION OF NEW JERSEY.

AIR-HEATER FOR CARBURETORS.

1,132,199.

Specification of Letters Patent.

Patented Mar. 16, 1915.

Application filed February 25, 1908. Serial No. 417,764.

To all whom it may concern:

Be it known that I, WILLIAM R. McKEEN, Jr., a citizen of the United States, residing at Omaha, in the county of Douglas and 5 State of Nebraska, have invented certain new and useful Improvements in Air-Heaters for Carburetors, of which the following is a full, clear, and exact description, such as will enable others skilled in the art to 10 which it appertains to make and use the same.

This invention relates broadly to internal combustion engines.

One of the objects thereof is to provide 15 simple and practical means for improving certain characteristics of the charge for an engine of the above type.

A more specific object is to provide efficient and reliable means for doing away 20 with certain difficulties found in starting internal combustion engines under conditions of cold weather.

Other objects will be in part obvious and in part pointed out hereinafter.

25 The invention accordingly consists in the features of construction, combinations of elements and arrangement of parts which will be exemplified in the construction hereinafter set forth, and the scope of the application of which will be indicated in the following claims.

In the accompanying drawing, wherein is shown one of various possible embodiments 30 of this invention, Figure 1 is a side elevation of the same partially broken away in order to disclose the structure more clearly, and showing its relation to the cylinder of an internal combustion engine. Fig. 2 is a detailed view of certain parts of the same, 35 shown partially in section and on a larger scale. Fig. 3 is an end or plan view of parts shown in Fig. 1.

Similar reference characters refer to similar parts throughout the several views of 40 the drawing.

In order to render clearer certain features 45 of this invention, it may be noted that in the starting of an internal combustion engine in cold weather difficulty has been found in properly exploding the charge. I have found that this is due chiefly to the fact that cold air does not readily and efficiently mix with the hydro-carbon to form a proper charge, and also to the effect of the 50 cold cylinder walls in condensing certain

constituents of the entering gas. The above and other defects are remedied in the constructions of the nature of that hereinafter described.

Referring now to the accompanying drawing, there is diagrammatically shown at 1 the cylinder of an internal combustion engine provided with a spark plug 2 or other igniting device, and such accessories as may permit the same to run under the internal combustion principle.

Leading to cylinder 1 is a conduit 3, any desired form of valve mechanism being interposed within the same, and connected with this conduit or passage is a carburetor 70 diagrammatically indicated at 4.

Leading to carburetor 4 are conduits 5 and 6 respectively adapted to conduct thereto hydro-carbon of any desired type and the air to be mixed therewith. Conduit 6 leads 75 from a metallic casing 7 closed at the lower end 8 and open at its upper end. Within this casing is a removable screen cylinder 9 loosely fitting the same, and having formed therein a plurality of screens 10 preferably 80 of concave form, and arranged alternately in inverse order in such manner as to build up a series of diaphragms through which the air passes.

Connected with the screen cylinder 9, as 85 by a reinforcing member 11 and links 12, is a handle 13 by which the screen may be removed from its casing.

The method of use and action of the above described embodiment of this invention is 90 substantially as follows: When it is desired to start the engine the screen members interposed in the casing 7 are heated and thus tend to heat the air passing through the same. This is preferably accomplished by 95 lifting the screen cylinder from the casing by the handle 13 and pouring a little gasoline or other fuel thereon, which is then ignited, and by its combustion brings the screen elements to a high temperature. 100 These screen members being of iron or copper tend to retain the heat, and upon being replaced in the casing 7 and the engine started, bring the entering air to a high temperature. This action is enhanced by reason 105 of the fact that the air is divided into fine streams in passing through the meshes of the various screens, and hence comes into intimate contact therewith. Also, the air is progressively heated by reason of the serial 110

disposition of the several screen dia-phragms, and when it passes into the carbureter it is at a high temperature. The lower screens, or those through which it passes last, by reason of their position at the bottom of the casing, tend to retain their heat longest, and hence aid in this progressive heating of the air by subjecting it to the hottest members after it has been tempered upon those through which it first passes. This highly heated air quickly vaporizes the hydro-carbon and forms a charge which is not only thoroughly mixed and otherwise efficient, but is of such temperature that upon its being slightly cooled by contact with the cold cylinder walls it is still so hot as to do away with any material condensing effect. It will be further apparent that when the screen is covered with oil, ignited and placed in the casing, and the engine cranked, not only is the air passing therethrough heated, but said air atomizes any unconsumed oil and the mixture is drawn into the combustion chamber where it serves the purpose of a charge. Thus it will be seen that the casing and screens act practically as an additional carbureter. The very hot mixture is readily ignited when starting, notwithstanding the fact that the combustion chamber may be cold.

It will thus be seen that there is provided apparatus of simple, inexpensive and durable construction, and highly efficient and practical action.

35 By the use of this apparatus as above set forth, the objects of this invention are achieved, and the starting of an internal combustion engine may readily be accomplished under all conditions of weather.

40 Having described my invention what I claim as new and desire to secure by Letters Patent is:

1. In combination with a carbureter having an air inlet pipe or passage, a heat-retaining body adapted to be readily inserted into and removed from said pipe or passage, and to be retained therein during operation of the carbureter; whereby it is adapted to be heated by means external to the carbureter, and thereafter placed in said passage and caused to heat air flowing through said passage.

2. In combination with a carbureter having an air inlet passage, a foraminous body mounted in and freely removable from said passage, whereby it is adapted to be re-

moved from and heated while outside the same, and thereafter to be replaced and caused to divide the inflowing air into small streams, and to heat the same.

60

3. In combination with a carbureter having an air inlet pipe or passage, a freely removable heat-retaining device adapted to be charged with liquid fuel and heated while removed from the air pipe or passage, and to be replaced therein while still in heated condition.

4. In combination with a carbureter having an air inlet pipe or passage, a foraminous body adapted to be freely introduced into and removed from said air inlet pipe, said body consisting of a plurality of pairs of concavo-convex screens placed base to base, one pair above another, and an encompassing screen serving to contain the series of screens and to maintain them in proper relative position.

5. In combination with a carbureter having an air inlet pipe or passage, a heater for use in starting in cold weather, comprising a foraminous body adapted to be freely introduced into and removed from the air inlet passage, and provided with a handle by which it may be inserted and removed, and by which it may be held during the heating of the body.

6. In combination with a carbureter and with a casing 7 communicating therewith, an air heater, comprising a cylinder 9, a series of pairs of concavo-convex screens 16 90 arranged base to base therein; and a handle 12, at the upper end of the cylinder.

7. In combination with a carbureter or charge-preparing device for internal combustion engines, said device having a mixing chamber and an air inlet passage or pipe; a heat-retaining body adapted to be freely inserted into and removed from said air pipe or passage in order that it may be heated by means external to the carbureter, 100 said body being of openwork construction whereby the inflowing air is permitted to flow through it and in contact with extended surfaces without being unduly impeded in its passage.

105

In testimony whereof I affix my signature, in the presence of two witnesses.

WILLIAM R. McKEEN, JR.
